UNITED STATES PATENT OFFICE.

GEORGE MASON TUCKER, OF KINGSTON, RHODE ISLAND.

DESIGN FOR A CRUCIBLE.

SPECIFICATION forming part of Design No. 33,632, dated December 4, 1900.

Application filed October 19, 1900. Serial No. 33,656. Term of patent 7 years.

To all whom it may concern:

Be it known that I, GEORGE MASON TUCKER, of Kingston, Rhode Island, have invented and produced a new and original Design for Crucibles, of which the following is a specification.

My design relates to a crucible, such as is commonly used for chemical determinations, &c.

10 My design consists in the configuration of

said crucible, which is in the form of an inverted conical frustum A, having a portion B of its wall inwardly inclined to the opening C.

I claim—

The design for a crucible as herein shown 15 and described.

GEORGE MASON TUCKER.
